United States Patent Office.

DARIUS PARKHURST, OF ST. LOUIS, MISSOURI.

Letters Patent No. 69,122, dated September 24, 1867.

IMPROVEMENT IN SAW-MILL HEAD-BLOCKS.

The Schedule referred to in these Letters Patent and making part of the same.

TO ALL WHOM IT MAY CONCERN:

Be it known that I, DARIUS PARKHURST, of the city and county of St. Louis, and State of Missouri, have invented a new and useful Improvement in Saw-Mill Head-Blocks and Carriages; and I do hereby declare that the following is a full and clear description thereof, reference being had to the accompanying drawings, and to the letters of reference marked thereon.

The object of this invention is to construct the head-blocks of a saw-mill in such a manner that either one or both of them may be moved at the same time by means of a single actuating lever, thus giving to that class of head-blocks known as self-acting the increased advantage of being moved further on one end than on the other, and then alternating the adjustment, thereby permitting the operator to saw tapering lumber, such as wheel-arms, wagon-tongues, fence-posts, and such other like tapering lumber.

To enable those skilled in the art to make and use my improved head-block and carriage, I will proceed to describe its construction and operation.

Figure 1 of the drawings is a side elevation of the improved carriage and head-block.

Figure 2 is a plan of the same.

Figure 3 is an end elevation of it.

Figure 4 is a sectional elevation of the end of one of the head-blocks, showing an application of a brake to it. A is the carriage, and in its general construction is not unlike other carriages used for similar purposes. The only improvement introduced in its construction is the plates α , which are securely fixed to its sides at such intervals as the tail-block B' will be likely to occupy when changed for different lengths of logs. The plates α , as clearly shown in fig. 2, are simply flat metallic plates, having notches cut in their inner edges of just sufficient size to receive the width of the head-blocks. When the block B' is to be placed on the carriage it will just be dropped into the notches thus prepared to receive it, and will thus be held securely in place on the carriage. The head-blocks B B' are each of them provided with the sliding rests C of the usual form. The bottom edges of these rests are provided with cogs, as seen in fig. 3. A pinion (not shown) in the central part of the head-block gears into and actuates the said rests either forward or backward, as may be required. These pinions are located on the same shafts as the bevel-wheels D, and are actuated by them, and those wheels D are in turn actuated by the bevel-wheels D', which are located on the inner ends of the shafts D², which have their bearings in the lugs b, projecting from the sides of the head-blocks B B'. There are levers E E' fixed to the outer ends of the shafts D², the positions of the said levers being vertical, or nearly vertical, and their upper ends terminating in handle pieces e e', while their lower ends extend downward a few inches, say six or eight, (more or less,) below the shafts D², and are there provided with wrists e² e³. A horizontal connecting-bar, F, connects the two wrists e² e³ together, as shown in fig. 1 of the drawings. One single circular orifice for the wrist e² is provided in the said connecting-bar, but a number of slots f are made in the bottom of the same for the reception of the wrist e³, the said slots f being disposed at intervals along the length of the said bar, the said intervals being arranged to suit the different locations of the block B'. As is clearly shown in fig. 3, the lower ends of the levers E E' are divided into two branches, between which are placed the cogged pinions G G', and also the ratchet-wheel g. The wheels G are securely fixed to the axles or shafts D², and the wheels G' and the ratchet g are placed on independent axles just above them, the latter axles finding their bearings in the two branches of the levers, and in such proximity to the shafts D² as to allow the cogs of G and G' to gear into each other. There are double pawls H H' pivoted to the outer sides of the levers E E', as clearly shown in fig. 1. The upper parts of these pawls are provided with handles h h', by means of which they may be thrown forward or backward at pleasure, so as to gear into the ratchets g. When the said pawls are thrown into contact with the said ratchets on either side, and the lever E or E' is operated forward or backward, as the case may be, the contact so formed between the said pawl and ratchet will lock the wheels g G', so they cannot revolve on their axes, and the wheel G will thereby be compelled to turn, and with it the gearing D D', and thus the sliding-rests C will be actuated either forward or backward, as may be desired. As each of the pawls H H' may be thrown into gear with its ratchet, either forward or backward, or out of gear entirely, by placing the handle h or h' parallel with the lever E or E', and as such contact of said pawls with their appropriate ratchets and the forward and backward motion of the levers E E' will cause motion to the aforesaid sliding rests C, either

forward or backward, and furthermore, as the bottoms of the levers E E' are connected together by means of the bar F , it follows that the operating of one of the levers E or E' , when both of the pawls are in gear on the corresponding sides of their respective ratchets, will actuate both of the slides C in harmony with each other, and when only one of the said pawls is in gear only one of the said slides C will be set in motion. As the pawls may be readily set in gear or out of gear by means of the handles h h' , it is evident that this arrangement of head-blocks will be very convenient where tapering stuff is to be sawed, and the whole arrangement of the gearing is so simple and efficient as to present much superiority over other head-block gearing now in use. A graduated disk, I , is attached to the outside of the lever E , and small perforations i in its periphery mark the graduation points. Into these perforations a pin may be inserted at any point desired, and when the said pin so inserted strikes the edge of the head-block it will stop the motion of the machinery, and the easy and rapid setting of the mill may be thus accomplished with great accuracy. It is the intention to place the perforations i in such relative positions to each other as to indicate quarter inches for the motion of the slide C . The thickness of the stuff sawed may thus be gauged with great accuracy. A lever, L , pivoted to the end of either of the head-blocks, has a turned-up end, which enters an annular groove, L , cut in the inner face of the wheel G , and by pressing the said lever to one side or the other a brake will be applied to the said wheel. A cam, L' , operated by a crank, l' , the said cam being pivoted to the end of the head-block in close proximity to the said lever, may be used for the purpose of applying the brake.

One great advantage of the employment of the head-blocks of the foregoing description is in the facility that is afforded for manufacturing lumber from springy logs, for by unshipping the pawl from its ratchet at either end, and reversing the motion at the other end of the carriage, the log at that end may be drawn back with the slide, provided that the log has been properly dogged.

Having described my invention, what I claim, is—

1. The combination of the levers E E' , pawls h h' , spur-gearings G G' , shafts D^2 , bevel-gearings D D' , and head-blocks C C , arranged in the manner described.
2. I claim the lever L , the cam L' , with its crank l' , and the wheel G , when combined and arranged in the manner and for the purpose set forth.

DARIUS PARKIURST.
